JOSEPH SACHS AND FRANK D. REYNOLDS, OF HARTFORD, CONNECTICUT, ASSIGNORS TO THE SACHS COMPANY, OF HARTFORD, CONNECTICUT, A CORPORATION OF CONNECTICUT.

SAFETY-FUSE.

No. 874,797.

Specification of Letters Patent.

Patented Dec. 24, 1907.

Application filed April 18, 1906, Serial No. 312,303. Renewed June 15, 1907. Serial No. 379,181.

To all whom it may concern:

Be it known that we, JOSEPH SACHS and FRANK D. REYNOLDS, citizens of the United States, residing at Hartford, in the county of 5 Hartford and State of Connecticut, have invented an Improvement in Safety-Fuses, of which the following is a specification.

Our invention relates to safety fuses and particularly to that class of safety fuses com- 10 monly known as indicating inclosed fuses.

Heretofore, indicating fuses have been constructed with an indicator wire wholly on the exterior of the fuse casing or the indicator wire has been essentially within the 15 casing with an indicating portion extending to the exterior surface thereof. In still other instances, the indicator wire has been employed entirely within the fuse casing and means have then been associated therewith 20 and situated in the walls of the casing or extending through the said walls to indicate the rupture of the fuse strip. In all of these instances however, so far as we are aware, the indicator wire, either directly or indi- 25 rectly, has been the means for indicating the rupture of the fuse strip.

As shown and described in our co-pending application Serial No. 310,045, filed April 5th, 1906, we have invented an indicator for 30 inclosed safety fuses in which we employ an indicating connection forming part of a circuit shunted across the terminals of the fuse device and located between the inside of an end cap and the tube, whereby we obtain a 35 direct, positive and clear indication of the blowing of the fuse. Now in our present invention, we have provided a similarly simple construction also embodying an indicating means electrically interposed between an 40 end cap and one end of a conductor electrically connected at the other end to the other end cap. In this case, the indicating means pass directly through the end cap, so as to be visible on the outer surface thereof and com- 45 prise or include a conducting indicating connection electrically connected with the end cap and one end of the conductor.

In carrying out our present invention, we employ a tube or casing, end caps therefor, a 50 fuse strip electrically connected to said end caps, a conductor connected at one end to one of said end caps, and an indicating means, including a conducting connection,

electrically interposed between the other end cap and the other end of the said conductor, 55 and extending through the end cap to the visible surface thereof. The indicating means extending to the surface of the end cap may be so constructed as to be ejected or dropped from position upon the blowing of the fuse 60 or the indicating conducting connection may extend to the surface of the end cap and be of such a material as to be merely changed in appearance by the heating, burning, disruption or other effect caused by the current, 65 or this connection may extend only part way to the surface of the end cap and may be covered by a plug or other means which is ejected by the disruption of the connection as will be hereinafter more particularly de- 70 scribed.

In the drawing, Figure 1 is a central longitudinal section of a safety fuse embodying our present invention. Fig. 2 is a plan of the same. Fig. 3 is a central longitudinal 75 section showing a modified form of our invention. Fig. 4 is an elevation of the left hand end of the device shown in Fig. 3, and Figs. 5 and 6 are end sections of further modifications of the invention. 80

a designates a tube made of any suitable insulating material, the ends of which we provide with suitable ferrules or end caps *b*, to which are electrically connected fuse terminals *c* and extending between the fuse 85 terminals *c* and electrically connected therewith, we employ a fuse strip *d*.

Referring particularly to Figs. 1 and 2, one of the end caps *b* is shown as provided with a suitable opening adapted to receive 90 a plug 2. The plug 2 is preferably passed through the body of the end cap *b* and into and partially through the adjacent portion of the tube *a*, the outer end of the plug being flush with the surface of the body of the end 95 cap.

e designates a wire electrically connected at one end to one of the end caps *b*, which wire *e* is passed longitudinally through the tube *a*, through an aperture therein imme- 100 diately below the recess provided for the reception of the plug 2, and is electrically connected at its opposite end with the said plug 2, which may be made of carbon, graphite or other similar substance or a mixture 105 of the same and a substance such as gun-

powder which will burn, discolor or otherwise change in appearance when heated by the current passing through it upon the blowing of the fuse, thereby providing an indicating conducting connection interposed between the end cap and one end of the conductor *e* and this plug may be of definite form before it is placed in the opening or it may be of plastic material which is molded into the opening and adapted to dry and harden therein. This is the preferred form of our invention, and in order to make a clearer indication we may whiten or otherwise color the visible portion of the indicating connection. Or as indicated in Figs. 3 and 4, we may employ a conical plug of graphite or carbon indicated at 4 adapted to fit into an aperture provided therefor in the end face of one of the end caps *b*, and this conical plug may be provided with a shank 5 to which one end of the shunt circuit wire *e* is wound, soldered, or otherwise electrically secured to make connection between these parts, the opposite end of the wire *e* being electrically connected to the other end cap *b* by being carried over the edge of the opposite end of the tube *a* and brought into contact with the inner surface of the end cap received thereon or otherwise. In this modification of the invention the plug 4 comprises a portion of the indicating means which are completed by the disruptible joint between the end of the conductor *e* and the shank 5 of the plug 4, wherein as will be apparent, the indicating means are electrically interposed between the end cap and the end of the conductor *e*, and that upon the disrupting of the joint after the blowing of the fuse, the plug will become loose or fall out of place to indicate such a condition.

As shown in Fig. 5, the plug 2 of graphite or other material may extend only part way through the aperture in the end cap and the remainder of the aperture be filled with an auxiliary plug 6, made of any suitable material, by which the blowing of the fuse is indicated. In this instance, as will be apparent, that while the conducting connection or plug 2 does not extend to the visible surface of the end cap, the indicating means comprising this plug 2 and the auxiliary plug 6 do so extend to the surface of the end cap. In this construction the material of the plug 2 may be of a conducting explosive nature such as a mixture of graphite and gunpowder which when heated by the current disrupts and blows out the plug 6.

Then again and as is shown in Fig 6, we may without departing from the nature and spirit of our invention, place a small quantity of gunpowder or other explosive material 7 at the base of the aperture in which the plug 2 is placed and beneath the said plug in order to forcibly eject the same upon the blowing of the fuse.

We may also employ a filling of insulating material in a loose condition within the tube, as indicated by the letter *f*.

We claim as our invention:

1. A safety fuse comprising a tube, terminals therefor, one of which is provided with an aperture, a fuse strip, a conductor, and an indicating means electrically interposed between one terminal and one end of the said conductor and located at the said aperture in the terminal. 70

2. A safety fuse comprising a tube, end caps therefor, one of which is provided with an aperture, a fuse strip, a conductor, and an indicating means electrically interposed between one of the said end caps and one end of the said conductor and located at the aperture in the end cap. 80

3. A safety fuse comprising a tube, terminals thereon, a fuse strip, a conductor, and an indicating connection electrically interposed between one terminal and one end of the said conductor and extending into an aperture in the said terminal. 85

4. A safety fuse comprising a tube, end caps therefor, a fuse strip, a conductor, and an indicating connection electrically interposed between one end cap and one end of the said conductor and extending into an aperture in said end cap. 90

5. A safety fuse comprising a tube, terminals therefor, a fuse strip, a conductor, and an indicating means interposed between one terminal and one end of the said conductor and extending into an aperture in the said terminal. 100

6. A safety fuse comprising a tube, end caps therefor, a fuse strip, a conductor, and an indicating means interposed between one end cap and one end of the said conductor and extending into an aperture in the said end cap. 105

7. A safety fuse comprising a tube, terminals therefor, a fuse strip, a conductor, and an indicating means interposed between one terminal and one end of the said conductor and extending through an aperture in the terminal to the visible surface thereof. 110

8. A safety fuse comprising a tube, terminals thereon, a fuse strip electrically connected to the said terminals, a conductor electrically connected at one end to one of the said terminals, the other terminal being provided with an aperture, and an indicating connection electrically interposed between the said other terminal and the other end of the said conductor and extending into the said aperture. 115

9. A safety fuse comprising a tube, terminals thereon, a fuse strip electrically connected to the said terminals, a conductor electrically connected at one end to one of the said terminals and an indicating means electrically interposed between the other terminal and the other end of the said conductor. 125

130

tor and extending through an aperture in the said other terminal to the visible surface thereof.

10. A safety fuse comprising a tube, terminals therefor, one of which is provided with an aperture, a fuse strip, a conductor, and a plug of conducting material electrically interposed between one terminal and one end of the said conductor and located at the said 10 aperture in the terminal.

11. A safety fuse comprising a tube, end caps therefor, a fuse strip, a conductor, and a plug of conducting material electrically interposed between one terminal and one end 15 of the said conductor and extending into an aperture in the said terminal.

12. A safety fuse comprising a tube, end caps therefor, a conductor, and a plug of conducting material electrically interposed between one terminal and one end of the said conductor and extending through an aperture in the said terminal to the visible surface thereof.

13. A safety fuse comprising a tube, end 25 caps therefor, a fuse strip, a conductor, connected at one end to one of said end caps, and

an indicating connection of resistance material electrically interposed between the other end of said conductor and the other end cap and located in an aperture in said other end 30 cap.

14. A safety fuse comprising a tube, end caps therefor, a fuse strip, a conductor directly connected at one end to one of said end caps, and an indicating connection composed of combustible and conducting material electrically interposed between the other end of said conductor, and the other end cap and located in an aperture in said end cap.

15. A safety fuse comprising a tube, end 40 caps therefor, a fuse strip, a conductor, and an indicating connection electrically interposed between one end of said conductor and one end cap and located in an aperture in said end cap and which is visibly changed 45 upon the rupture of said fuse strip.

Signed by us this 28th day of March 1906.
